UNITED STATES PATENT OFFICE.

JOHN W. NIDAY, OF UNIONVILLE, MISSOURI, ASSIGNOR OF ONE-HALF TO THOMAS E. ROBINSON, OF UNIONVILLE, MISSOURI.

DOOR-HOLDER.

No. 893,009.

Specification of Letters Patent.

Patented July 14, 1908.

Application filed December 28, 1906, Serial No. 349,838. Renewed May 23, 1908. Serial No. 434,544.

To all whom it may concern:

Be it known that I, JOHN W. NIDAY, a citizen of the United States, residing at Unionville, in the county of Putnam and State of Missouri, have invented a new and useful 5 Door-Holder, of which the following is a specification.

This invention relates to door holders such as are adapted to be used for clamping a 10 door in fixed position during the operation of applying the hinges or trimming down the edges thereof.

The objects of the invention are to improve and simplify the construction of such 15 devices; furthermore, to increase their efficiency in operation and to decrease the expense attending their manufacture.

With the foregoing and other objects in view, which will appear as the description 20 proceeds, the invention resides in the combination and arrangement of parts and in the details of construction hereinafter described and claimed it being understood that changes in the precise embodiment of invention here- 25 disclosed can be made within the scope of the following claims without departing from the spirit of the invention or sacrificing any of its advantages.

In the accompanying drawings forming 30 part of this specification:—Figure 1 is a front elevation of a door holder constructed in accordance with the invention; Fig. 2 is a similar view, partly in section; Fig. 3 is a vertical section through one of the jaws; and Fig. 4 is 35 a perspective view showing the inner side ends of the threaded rods separated from each other.

Like reference numerals indicate corresponding parts in the different figures of the 40 drawing.

The reference numerals 1 and 2 indicate a pair of jaws, the opposing faces of which are adapted to be fitted against the sides of a door for holding the same securely in position 45 during the operation of trimming down the edges thereof or applying the hinges preparatory to fitting the door into the door casing. The jaws 1 and 2 preferably are connected with each other in an adjustable manner by 50 means of a link device indicated generally by the reference numeral 3, said link device consisting of a pair of threaded rods 4—5 having a pivotal connection with each other. The

preferred form of pivotal connection between the threaded rods 4 and 5 consists of an approximately wedge-shaped ear 6 adapted to fit into a wedge-shaped slot 7 formed in the end of the rod 4, the ear 6 being formed with a perforation 8 to receive a pin 9 adapted to be passed through the perforations 10 in the bifurcated end of the rod 4. Each of the jaws 1 and 2 is formed with a bore 11 to receive one of the threaded rods of the link device. The bore 11 of each jaw at one point is intersected by a socket 12 extending upward from the lower end of the jaw and adapted to hold securely in position a nut 13 which is of practically the same size as the width of the socket 12 so as to be held stationary therein and thus be incapable of rotation. Each of the rods 4 and 5 of the link device extends through the bore 11 of one of the jaws and is engaged with the nut 13.

It will be obvious from the foregoing description that the pivotally connected threaded rods 4 and 5 constitute the sole connection between the jaws 1 and 2, and that by taking the jaws one in each hand and rotating them in opposite directions, they can be easily and quickly adjusted toward or away from each other until they are the proper distance apart to fit the door. When the jaws have been adjusted so that they are of approximately the proper size to fit a door, said jaws can be separated from each other 85 at their upper ends, this movement being permitted by the pivotal connection of the rods 4 and 5, so that the space between the jaws will be wedged-shaped and can be easily fitted over the edge of the door so that when 90 the two jaws are fitted flat against the floor, the opposing faces of the jaws will be moved into parallelism with each other, and will thus secure a firm grip upon the door.

The means for anchoring the door holder 95 upon a floor, so as to prevent it from slipping during the operation of trimming a door, preferably consists of a hook or catch 15 having a pointed forward end 16 and an eye 17 at its inner end engaged with an eye 18 connected 100 with the jaw 1. It will be obvious that after the jaws have been properly engaged with the door, the holder can be locked in position by hammering the point 16 of the hook 15 into the floor.

The improved door holder of this inven-

tion is strong, simple, durable and inexpensive in construction as well as thoroughly efficient in operation.

What is claimed is:

- 5 1. A door holder comprising a pair of jaws, and a pair of pivotally connected threaded rods constituting the sole connection between said jaws.
- 10 2. A door holder comprising a pair of jaws each having a socket provided with a threaded member, and a pair of pivotally connected threaded rods engaging the sockets of said jaws and adjustably connecting the same with each other.
- 15 3. A door holder comprising a pair of jaws each having a bore intersected by a socket extending upward from the lower end thereof, a nut stationarily mounted in each of said sockets, a pair of pivotally mounted threaded rods, each of said rods extending through the bore in one of said jaws and having a threaded engagement with the nut in the socket of said jaw, and an anchoring device connected with one of said jaws.

124. A door holder comprising a pair of jaws each having a bore, a socket intersecting said bore and extending upward from the lower end of the jaw, a nut mounted in each of said sockets, a pair of threaded rods, one of said rods having a wedged-shaped slot in one end and the other of said rods having a wedge-shaped ear to fit said wedge-shaped slot, a pivot pin extending through the interfitting ends of said threaded rods, and a hook pivotally connected with one of said jaws and having a pointed end.

5. A door holder comprising a pair of jaws, and a pair of pivotally connected rods constituting the sole connection between said jaws.

In testimony that I claim the foregoing as my own, I have hereto affixed my signature in the presence of two witnesses.

JOHN W. NIDAY.
